ABSTRACT: A reusable container closure utilizing a cap with an integral skirt. The skirt has an enlarged obstruction section separating upper and lower circumferential grooves, which are adapted to receive a retainer ring. With the retainer ring in the lower groove, an enlarged sealing section of the skirt engages the neck of the container to effect a seal. The cap is removed to the upper groove by pulling a tab on the skirt until the obstruction section is reduced in diameter sufficiently to permit the clamping ring to be forced out of the lower groove and into the upper groove.

CONTAINER CLOSURE WITH LOCKING RING

This invention relates to improvements in container closures.

In providing closures for bottles or the like, the closure must be capable of providing an effective seal to keep the contents within the bottle. If the contents are under pressure, the sealing requirements become somewhat more exacting. Also, a closure that can be hand removed and subsequently reused, when desired, has many advantages.

With the foregoing in mind, a new and different container closure is contemplated utilizing a retainer ring to facilitate closure reduction and sealing and that can be stored on the closure until the closure is to be reused and also by its construction utilizes the pressure within the container to assist in maintaining the seal.

Further contemplated is a closure that has a unique provision for moving a retainer ring from a clamping position for sealing purposes to a storing position until the closure is to be reused by a simple lifting motion applied to a tab on the closure.

Another objective is to provide a container closure that has a pull tab formed integral with a skirt on the closure and upon the initial pull commences venting after which the closure is released from the container.

More specifically contemplated is a reusable closure that utilizes a retainer ring which is moved back and forth between clamping and storing positions on the closure skirt by displacing an obstruction section on the skirt through the agency of a pull tab depending from the skirt of the closure and that has a novel construction for providing both primary and secondary seals.

The foregoing and other objects and advantages of the invention will become apparent from the following description and from the accompanying drawings in which:

FIG. 1 shows a vertical sectional view of a container with a closure incorporating the principles of the invention installed thereon;

FIG. 2 is another vertical sectional view taken along line 2-2 of FIGURE 4, the closure being shown in the released position on the container;

FIG. 3 is a plan view of the closure in which the pull ring and tab are deflected horizontally for ease of illustration; and

FIG. 4 is an elevational view, partly in section, of the container and closure of FIG. 1, the closure being shown in the container sealing position thereon.

Referring now to the drawings and first to FIGURE 1, the numeral 10 denotes a container such as a bottle or the like, with a neck bead 12, the container 10 can be formed of any well-known material; e.g., glass, plastic, or metal. The closure for the container is designated generally at 14 and includes a cap 16 and a retainer ring 18.

The cap 16 is formed of some relatively stiff plasticlike material, such as polyethylene and has a top 20 from which depends an integral skirt 22. The skirt 22 is provided with upper and lower circumferential grooves 24 and 26. These grooves 24 and 26 are separated by an enlarged obstruction section 28 that extends outwardly from and is arranged adjacent to the container neck bead 12. The upper groove 24 includes the adjacent annular corner enlargement 33 which retains ring 18 on the closure.

Downwardly from this obstruction section 28, and on the inside of the skirt 22 is an enlarged sealing section 30. The enlarged sealing section 30 preferably has a smaller diameter in the relaxed position than the diameter of the neck bead 12 and is tapered to present somewhat of a frustoconical shape so that the cap 16 snaps onto the container 10 and then, as displayed in FIG. 1, has a substantial area in sealing engagement with the neck of the container 10. Therefore, with the retainer ring 18 in the illustrated position, a downward force is imposed upon the cap 16 for both urging the sealing section 30 into engagement with the neck of the container 10 to effect a primary seal and the cap 16 into tighter engagement with the neck bead 12 to effect a secondary seal.

The retainer ring 18 is expandable so as to have a smaller diameter than the circumferential groove 26 and must be capable of expanding to move into and out of this groove 26 without becoming permanently deformed. Suitable materials for the purpose include rubber or some kind of plastic or a coil spring can be used.

It is noteworthy that in the FIG. 1 position with the retainer ring 18 in the clamping position, a positive pressure within the container 10 will act on the cap top 20 and tend to urge it upwardly. This upward force enhances the seal around the neck bead 12 because of the aforementioned conical shape of the sealing section 30 and the clamping action of the retainer ring 18. Also, if the pressure is a vacuum; i.e., a negative pressure, there is a tendency for the cap 16 then to be pulled into tighter engagement with the neck bead 12. Thus, it will be appreciated with this structural arrangement, either negative or positive pressures will actually improve the sealing relationship between the closure 14 and the container 10.

For removing the closure 14, a tab 31 which is integral with and depends downwardly from the skirt 22 of the cap 16 is provided with ring pull 32. This tab 31 is pulled outwardly and upwardly from the FIG. 3 position and to FIG. 4 position. This causes the enlarged obstruction section 28 (FIGS. 1 and 2) to be forced against a neck bead 12 which serves as a pivot joint. Hence, the obstruction section 28 is displaced so that its diameter is reduced until small enough for the retainer ring 18 to be forced by the lifting action on the tab 31, past the obstruction section 28 and into the upper groove 24, as shown in FIG. 2. During this lifting of the tab 31, the seals afforded by the sealing section 30 and that at the neck bead 12 commence to release and venting will be initiated and be substantially completed by the time the retainer ring 18 is shifted into the upper groove 24.

Now, with the retainer ring 18 in the upper groove 24, the entire closure 14 can be removed and the contents of the container 10 emptied. If the container 10 is only partially emptied, the closure 14 can be replaced by forcing it back onto the neck bead 12. The retainer ring 18 is then moved from the upper groove 24 into the lower groove 26 and the primary and secondary seals are again effective between the closure 14 and the container 10.

From the foregoing it will be appreciated that by a simple rollout lifting motion of the tab 31, 32, the closure 14 can easily be removed from the container 10. The retainer ring 18 never separates from the cap 16 and becomes lost or has to be destroyed, but is stored in the upper groove 24 and retained by annular corner enlargement 33 until the closure is to be reused. Also, the closure 14 not only provides effective primary and secondary seals, but the arrangement is such that the pressure within the container 10, whether negative or positive, enhances the sealing.

What is claimed is:

1. A reusable manually removable and replaceable closure for a container having an outwardly flared neck portion terminating in a neck bead on the outer periphery of the container finish, said closure comprising a cap of resilient plastic material having a top and an integral depending annular skirt, the outer side of said skirt having an outwardly projecting annular obstruction section located in axially coextensive radial alignment with said neck bead when said closure is seated upon said container, means defining a pair of annular grooves in the outer side of said skirt separated by and located respectively immediately above and below said obstruction section, a downwardly and inwardly inclined annular seating section on the inner side of said skirt having a maximum diameter portion corresponding to the outer diameter of said neck bead and located in radial alignment with said obstruction section, a tab portion integral with and projecting downwardly from the lower edge of said skirt, and a resilient retainer ring normally seated in one of said grooves and movable across said obstruction section from the lower of said grooves to the upper of said grooves by radial outward flexing of said tab portion, said ring being manually movable from said upper of said grooves

across said obstruction section to the lower of said grooves
when said cap is seated on said container to sealingly lock said
closure to said container.
